CHAIR

Robert E. Kjer Jakobsen, Manhattan Beach, Calif., assignor to Schlumberger Limited, Houston, Tex., a corporation of the Netherlands Antilles

Filed Mar. 31, 1964, Ser. No. 79,264

Term of patent 14 years

(Cl. D15—8)

FIG. 1 is a rear perspective view of a chair, showing my design; and

FIG. 2 is a front perspective view thereof.

The design is characterized by the back comprised of the outer framing members in association with the upwardly diverging strut members, the arcuate interconnecting bridge, and the specifically configured back rest cushion, all as shown.

I claim:

The ornamental design for a chair, substantially as shown and described.
